UNITED STATES PATENT OFFICE

162,609

TELEVISION CABINET CONTROL PANEL

Samuel E. Adler, Chicago, Ill.

Application May 11, 1950, Serial No. 9,865

Term of patent 14 years

(Cl. D26—1)

To all whom it may concern:

Be it known that I, Samuel E. Adler, a citizen of the United States, residing at Chicago, in the county of Cook, State of Illinois, have invented a new, original, and ornamental Design for a Television Cabinet Control Panel, of which the following is a specification, reference being had to the accompanying drawings, forming a part thereof.

Fig. 1 is a front elevational view of a television cabinet control panel, embodying my new design;

Fig. 2 is a top plan view thereof;

Fig. 3 is an end elevational view of the same;

Fig. 4 is a sectional view on line 4—4 of Fig. 1;

Fig. 5 is a front elevational view of the panel, a door thereof being shown in open position;

Fig. 6 is a top plan view of the panel in the position it is shown in Fig. 5.

Fig. 7 is an end view of the panel as depicted in Figs. 5 and 6;

Fig. 8 is a sectional view on line 8—8 of Fig. 5.

The dominant features of my design resides in that portion shown in full lines in the drawings.

I claim:

The ornamental design for a television cabinet control panel, as shown and described.

SAMUEL E. ADLER.
